UNITED STATES PATENT OFFICE

CHARLES TAYLOR WALTER, OF CHICAGO, ILLINOIS, ASSIGNOR TO SWIFT AND COMPANY, OF CHICAGO, ILLINOIS, A CORPORATION OF ILLINOIS

MEAT PACKING CONVEYER

Application filed January 5, 1931. Serial No. 506,652.

This invention relates to methods and means for arranging products such as sliced bacon for economical packing and means for carrying out the method. One of the objects 5 of the invention is to provide a moving conveyer to carry sliced product away from the slicing means, which conveyer is adapted to easy removal of the product.

Another object of the invention is to provide a means for removing the product from the conveyer.

It is conventional practice in packing sliced bacon to cause the slices as they come from the slicing machine to fall in pans, an operator 15 counting the slices as they fall or determining the quantity in the pan by scaling means, the pans being then placed upon a belt conveyer to be carried to the packers who must arrange the slices in spaced relation 20 in order to make an attractive merchantable package.

It is possible to cause slices of bacon to fall upon a conveyer in accurately spaced relationship as described in my copending 25 application entitled "Meat packing method," filed January 5, 1932, Serial 506,653.

The object of my present invention is to utilize to the fullest extent the benefits to be derived from causing bacon to be accurately 30 spaced upon a moving conveyer. In the accompanying drawing which forms a part of this specification similar numerals or references in similar figures indicate similar parts.

Figure 1 is a plan view of one unit of the conveyer.

Figure 2 is an end view of one end of the conveyer.

Figure 3 is a prospective view of one unit 40 of the conveyer.

It should be noted that the apron or belt consists of a plurality of corrugated units presenting in assembly a flat surface traversed lengthwise by a plurality of depressions or grooves. The several units as 1, are identical, each one having its extremities projecting in the form of rigid, flat supporting portions 2 and 3 to slidably or otherwise rest on angle irons 4 and 5. Two chains, 45 6 and 7, join the several units. The chains 50

run on appropriate sprocket wheels such as 8. The depressions 9 are clearly shown in Figures 1 and 3. The speed of the conveyer being synchronized with the speed of the slicing machine, I have found that when both 55 the conveyer and the slicing machine are each operated at a uniform speed, with any desired constant relationship between the two speeds, that the bacon slices fall upon the conveyer in constant spaced relationship to 60 each other. The amount of this spacing may be altered by changing either the machine speed or the conveyer speed. The conveyer may be operated at a variable speed 65 properly synchronized with the slicing machine to cause groups of slices to be not uniformly spaced as for example, the slices to be spaced closer together at the center of the group than at the ends of the group. This same effect may be produced by maintaining the conveyer speed constant and the 70 rotative speed of the slicing knife constant and giving the slicing machine an oscillatory motion in the direction of the conveyer motion. The slices fall upon the conveyer in 75 the proper relation to each other for packing. To carry out my method I may employ a fork not shown.

It will be understood that while my invention may be practiced with slicing machines 80 of various types and irrespective of the nature of the product and that changes may be made in the design in details of the invention as herein illustrated, it might be noted that the invention is particularly applicable for co-operation and use with a slicing machine of a type such as particularly described and claimed in my copending application filed June 11, 1931, Serial No. 543,499.

I claim:

1. An endless belt type of conveyer comprising a plurality of parallel members, each member being formed of a continuous piece of flat material and bent at intervals to provide parallel grooves, the extremities of 95 each member being disposed in horizontal alignment with each other and substantially in the horizontal plane of the upper surfaces of the respective members to form rigid, projecting, flat supporting portions for the mem- 100

bers, the grooves of said members aligning when the members are assembled and the grooves running in the direction of motion of the conveyer, and parallel endless sprocket chains connecting said members on the undersides thereof below the horizontal plane of said supporting portions.

2. An endless belt type of conveyer comprising a plurality of parallel members, each member being formed of a continuous piece of flat material and bent at intervals to provide parallel grooves, the extremities of each member being disposed in horizontal alignment with each other and substantially in the horizontal plane of the upper surfaces of the respective members to form rigid, projecting, flat supporting portions for the members, the grooves of said members aligning when the members are assembled and the grooves running in the direction of motion of the conveyer, and endless sprocket chains each rigidly secured to the bottoms of certain of the grooves of each of said members and within the vertical plane of said supporting portions.

Signed at Chicago, Illinois, this 3rd day of January, A. D. 1931.

CHARLES TAYLOR WALTER.
